DES. 2048

Oliver J. Key of Lowell Massachusetts

Assignee to

Lowell Manufacturing Company of the same place

Letters Patent No. 2048. Dated April 11. 1865.

Design for a Carpet Pattern

The schedule referred to in these Letters Patent and making part of the same.

To all whom it may concern:

Be it known that I, Oliver J. Key, of Lowell, in the County of Middlesex, and State of Massachusetts, have originated and designed a new Pattern for carpets or other fabrics, of which the following is a full, clear and exact description, reference being had to the accompanying drawings, making part of this specification.

A is a sprig of leaves, surrounded by the frame B, the particular form of it is shown in the drawing.

1,1,1,1 and 2,2,2,2, in the corners when matched will form a figure similar to A and B.

C,C,C,C are leaves of a diamond shaped figure.

D,D,D,D is a sprig work connecting the Design.

The colors employed for the different portions of the design, may be varied to suit the taste and wish of the manufacturer.

Claims.

What I claim as my invention and desire to secure by Letters Patent, is
2.2.11. the Design or Pattern for carpets, or other fabrics, herein set forth.

Witnesses.
